UNITED STATES PATENT OFFICE.

EMANUEL C. GIPE, OF CHICAGO, ILLINOIS, ASSIGNOR OF THREE-FOURTHS
TO FELIX J. GRIFFEN, OF SAME PLACE, HENRY GLOS, OF ELMHURST,
ILLINOIS, AND GEORGE W. TASSELL, OF WAUKESHA, WISCONSIN.

STORE-SERVICE APPARATUS.

SPECIFICATION forming part of Letters Patent No. 660,100, dated October 23, 1900.

Application filed February 26, 1900. Serial No. 6,522. (No model.)

To all whom it may concern:

Be it known that I, EMANUEL C. GIPE, of Chicago, in the county of Cook and State of Illinois, have invented certain new and useful Improvements in Store-Service Apparatus, of which the following is a full, clear, and exact description, reference being had to the accompanying drawings, forming a part of this specification, in which similar numerals 10 of reference in the different figures indicate like parts.

My invention has reference particularly to cash-carrier mechanism adapted for use in stores; and my object is to so devise said mechanism that it may be simple, compact, attractive, and cheaply constructed; and among other things I desire to provide means whereby the cord propelling mechanism may be simplified, rendered more certain and positive in action with a relatively-short pull of the cord, while entanglements thereof may be avoided. I accomplish this end by combining with a wireway and car a propelling-cord having a loop arranged in the pathway 25 of the car and adapted to be engaged thereby, said propelling-cord being trained back and forth over multiplying-pulleys supported by means of a separate wire arranged parallel to the wireway, a pull or actuating cord adapted to be operated by an impulse of the hand, and a sliding take-up interposed between said propelling-cord and pull-cord, said take-up being provided with a spring adapted to exert a yielding resilient action upon both of said 30 cords, whereby the slack in both may be taken up and the handle of the pull-cord maintained in a predetermined normal position, all of which is hereinafter more particularly described and definitely claimed.

40 In the drawings, Figure 1 is a side view in elevation of a cash-carrying apparatus embodying the features of my invention. Fig. 2 is a detail view of the cord take-up and handle-lifting device, a portion thereof being shown in longitudinal section. Fig. 3 is an enlarged side view in detail of a portion of the fixtures which support the wire and cord propelling mechanism at the "salesman's end." Fig. 4 is a plan view thereof. Fig. 5

is a similar view to that represented in Fig. 3, the same being shown in vertical section. Fig. 6 is an enlarged plan view of the cord propelling mechanism. Fig. 7 is a front view thereof, taken upon the line 7 7, Fig. 6, as viewed in the direction of the arrow there 55 shown. Fig. 8 is a side view of the parts shown in Fig. 6. Fig. 9 is a side view of the wire and cord supporting mechanism at the "cashier's end." Fig. 10 is a transverse vertical sectional view thereof; and Fig. 11 is a 60 similar view to that shown in Fig. 9, except that it is partly in longitudinal section.

Referring to the drawings, 1 2, Fig. 1, represent the usual depending ceiling posts or hangers, which are tapped into ceiling-plates 65 3 3, rigidly attached to the ceiling. Upon the lower end of the hanger 1 is secured a metal casting 4, (more clearly shown in Figs. 3, 4, and 5,) having rings 5 5, adapted to receive the hanger 1, as shown in Fig. 1. Said 70 rings are connected by means of a flat portion or web 6, to the upper end of which is pivotally connected at 7 a casting 8, while to the lower end at 9 is attached in like manner a somewhat-similar casting 10 for the purposes 75 hereinafter stated. Mounted upon the hanger 1 and interposed between the rings 5 5 is a two-part clamp 11, bolted or riveted together, as shown, to which is attached an anchor-wire 12. A similar clamp 13 is secured to the lower 80 end of the hanger 2, to which is attached a brace rod or wire 14. The casting 8 is made in two parts, between which is interposed a ratchet-wheel 15, Fig. 5, mounted upon a shaft 16, having a polygonal projecting head 17, 85 Fig. 3. A pawl 18 is also pivotally secured within said casting. A pin or rivet 19 serves to connect the two halves of said casting at the outer end. A pawl 20 and ratchet 21 are interposed in like manner between the members of the two-part casting 10.

Upon the shaft 16 is wound a supporting-wire 22 for the purpose of sustaining one end of the cord propelling mechanism, as herein-after stated, while a similar wire 23, which forms the way upon which the car runs, is secured to the shaft 24, upon which the ratchet-wheel 20 is mounted. Said wires are attached

to similar castings 25 and 26, respectively, at the opposite end, special features of which will be hereinafter explained, and the wires are made taut by turning the shafts 16 and 24.

5 Parallel rods 27, which are preferably integral with each other, are bent at right angles at the rear end, so as to form a cross-bar 28, (better shown in Fig. 5 and indicated in dotted lines in Fig. 4,) which cross-bar is inserted 10 in a notch 29, formed in the top of the parts 8 and 25, respectively, and held in place by means of pins arranged to bar the opening of the notch, as shown. The opposite ends of the rods 27 are rigidly secured in bores formed 15 in lugs 30 30 in two-part castings, which are secured to each other by means of rivets 31 32, as shown in Figs. 7 and 8. The upper part of said casting forms a head 33, in which is mounted a double grooved pulley 34, (shown 20 in Figs. 6 and 7 and indicated in dotted lines in Figs. 1 and 8,) while the lower part forms obliquely-disposed casings 35 35, in each of which is mounted a pulley 36. (Better shown 25 in Fig. 7.) The pulley-casings 35 are made to straddle the wire 22, which wire serves as a support therefor, thereby maintaining the rods 27 in a horizontal position or in one parallel to that of the wires 22 and 23, whether 30 horizontal or inclined.

30 Loosely mounted upon and supported by means of laterally-extended arms 37, Figs. 1, 6, and 8, is a sliding head 38, (also shown in Fig. 2,) which is provided with a tubular extension 39, into which is inserted a tube 40, 35 which is secured in place by means of a pin 41. The other end of the tube is secured in a bore formed in a sliding head 42, Figs. 1 and 2, which is in turn supported upon the rods 27 by means of arms 43 43. (Better shown in 40 Fig. 4.) Within the tube 40 is loosely inserted a piston 44, Fig. 2, to which is attached a cord 45, which cord is extended through the tube and outwardly over a pulley 46, and thence downwardly through a suitable bore or opening, as shown. A handle 47, Fig. 1, is attached to the lower end of the cord, which, engaging with the fixtures upon the lower ends of the hangers, forms a stop to limit the upward movement of the cord 45, which I term 45 50 the "actuating" or "pull" cord. A spiral spring 48 is inserted within the tube 40, said spring being interposed between the piston 44 and the end of the tube, as shown in Fig. 2, which serves normally to retain said piston 55 in the position shown in said figure.

Secured in bores in the head 38 are the two ends of a propelling-cord 49, Figs. 1, 2, 6, 7, and 8, which is extended out from the head in parallel lines, as shown in Fig. 6, thence 60 over the double grooved pulley 34, thence back over a like pulley 50, (shown in full lines in Fig. 2 and in dotted lines in Figs. 6 and 8,) thence forward over the obliquely-placed pulleys 36 36, terminating in a loop 51, which 65 rests upon the wire 23, as shown in Figs. 1, 6, and 8, the normal position of said loop being shown at the right in Fig. 1. The length

of the cords 49 and 45 are such and they are so adjusted, respectively, with reference to the spring 48 that when the latter is expanded, 70 as shown in Fig. 2, the handle 47 of the pull-cord is drawn upwardly against the part 5, as shown at the right in Fig. 1, while the slide, consisting of the parts 38 and 42 and the connecting-tube 40, is drawn back to the position 75 shown at the right in said Fig. 1. This causes the cord 49 to be placed under slight tension sufficient to prevent entanglement or disarrangement while the loop 51 is drawn close to the case 35, the various parts being represented in normal positions as they would appear immediately upon discharging the car for transmission over the line. In Fig. 1 the cash-car 52, which is provided with catches 53 54 for engagement with the loops at the 80 respective ends, is shown in engagement with the loop at one end, the momentum of the car being sufficient to compress the spring 48, which enables the loop 51 to be drawn back with the car to the end of the line, it being 85 understood that the object of placing the pulleys 36 obliquely to each other is to enable the car to pass back and forth between them, while insuring alinement at the top between the cords and the respective grooves of the 90 pulley 50. When the car is in the position as shown at the left in Fig. 1, the slide mechanism containing the spring is drawn forward.

It will be seen from the foregoing that the 95 interposition of the spring and slide mechanism, constituting an automatic take-up, serves a double purpose—viz., to keep the handle 47 in the desired normal position out of the way and to maintain the respective cords at all 100 times under tension, thereby avoiding entanglement and insuring certainty in the action 105 of the parts.

The parts 25 and 26 are provided with 110 sockets which are mounted upon balls 55 56, (better shown in Fig. 11,) said balls being integral with plates 56, which are bolted to a horizontal bar 57, bolted to the lower ends of hangers 2, arranged side by side, one of which is shown in Fig. 1. The construction shown 115 enables the wire supports or connections 8, 10, 25, and 26 to adapt themselves to the relative positions of the wires, whether horizontal or inclined, while the rods 27 are obviously 120 free to assume parallelism with said wires.

The advantages of my improved device are 125 obvious in that they render the system compact, simple, and attractive. The propelling mechanism may be applied at one or both ends and is applicable to horizontal or inclined wires and to special and varying conditions met with in different stores.

Having thus described my invention, I claim—

1. In a device of the class described, the combination with a car and wireway, of a 130 supporting-wire arranged parallel to said wireway, a propelling-cord having a loop adapted to be engaged by said car, a series of pulleys over which said propelling-cord is

- trained, an actuating-cord and a sliding spring-controlled take-up interposed between said propelling and actuating cords respectively, and in operative connection therewith, whereby the slack in the propelling-cord may be taken up and the handle of the actuating-cord held normally in a predetermined position, substantially as described.
2. In a device of the class described, the combination with a car and wireway, of a supporting-wire arranged parallel with said wireway, parallel rods extending forward from the supporting-hanger, stationary pulleys attached to the forward end of said rods, a sliding take-up mounted upon said rods, a pulley upon the forward end of said take-up, a propelling-cord attached to the end of said take-up, thence carried forward over said pulleys, thence back over a pulley upon said take-up, thence forward over the remaining stationary pulleys behind which said cord is looped in the path of the car, a coiled spring arranged within a guide in said sliding take-up and an actuating-cord attached to the forward end of said spring and trained over a suitable pulley, substantially as described.
3. In a device of the class described, the combination of a wireway, rigid supports for sustaining said wireway, a sliding take-up, means for supporting the same in operative proximity to one of said supports, a propelling-cord attached to said sliding take-up, a series of multiplying-pulleys interposed between the same and said car, a coiled spring mounted upon said take-up, and an actuating-cord connected with the forward end of said coiled spring, whereby the latter may act simultaneously upon said propelling and actuating cords to take up the slack in the one and to maintain the other in a predetermined normal position, substantially as described.
4. In a cash-car system, the combination of a car, a wireway stretched between rigid supports, a stretched supplemental wire arranged above and parallel with said wireway, parallel rods having their rear ends attached to one of said rigid supports while the forward ends thereof are supported by said supplemental wire, multiplying-pulleys secured to the forward end of said rods, a sliding take-up loosely mounted upon said rods, a double grooved pulley upon said take-up, a propelling-cord attached to said take-up and trained back and forth over said multiplying-pulleys and said take-up pulley, said propelling-cord having a loop lying in the path of movement of the car, a coiled spring in operative connection with said take-up, a pull or actuating cord connected with the forward end of said coiled spring, and a suitable stop

for limiting the movement of said pull-cord, substantially as described.

5. In a device of the class described, the combination with a car and wireway, of a supporting-wire arranged parallel to said wireway, rods placed parallel to said supporting-wire, a sliding take-up mounted upon said rods, propelling and actuating cords respectively in operative connection with said take-up, a coiled spring mounted upon said take-up and connected directly with one of said cords for the purpose of taking up the slack in both, pulleys 34, 50, and the obliquely-disposed pulleys 36, over which the propelling-cord is trained in the manner and for the purpose substantially as shown and described.

6. The combination with a wireway, a parallel supporting-wire and parallel rods 27, of a sliding take-up loosely mounted upon said rods, coiled spring 48 disposed within a tube forming a part of said take-up, cords 45, 49, extending in opposite directions, one connected with said spring and the other with the body of said take-up, pulley 46 at the rear of said parallel rods, pulley 34 mounted in bearings at the forward end of said rods, pulley 50 upon the forward end of said take-up, and the obliquely-disposed pulleys 36, the grooves in the top of which are in alignment with those in the pulley 50, while the bottoms of said pulleys are arranged to straddle the wireway to permit the body of the car to pass between and engage the loop of the propelling-cord, substantially as described.

7. The combination in a device of the class described, of a wireway, a parallel supporting-wire arranged above said wireway, parallel rods for supporting a sliding take-up, a sliding take-up, pull and propelling cords respectively, arranged to oppose each other at opposite ends of said take-up, suitable pulleys for mounting said cords, and independent pivotal supports at the respective ends for each of said wires, whereby the wires may be disposed in any desired position, inclined or horizontal, while parallelism may be maintained between the wires and the take-up rods, and the grooves of the coacting pulleys kept in alignment, substantially as described.

In testimony whereof I have signed this specification, in the presence of two subscribing witnesses, this 21st day of February, 1900.

EMANUEL C. GIPE.
